[57] CLAIM

The ornamental design for a inflatable cushion for use in the rear passenger area of an automobile, as shown and described.

DESCRIPTION

FIG. 1 is a perspective view of an inflatable cushion for use in the rear passenger area of an automobile showing my new design;

FIG. 2 is a front elevational view thereof;

FIG. 3 is a top plan view thereof;

FIG. 4 is a bottom plan view thereof;

FIG. 5 is a side elevational view thereof, the opposite side being a mirror image of that shown;

FIG. 6 is a perspective view thereof, shown in an alter-

native configuration; and

FIG. 7 is a perspective view thereof, shown with por-

tions deflated in another alternative configuration.

FIG. 1

FIG. 2

FIG. 3

FIG. 4

FIG. 5

FIG. 6

FIG. 7
